UNITED STATES PATENT OFFICE.

WALTER W. HUNZICKER, OF MANSFIELD, OHIO, ASSIGNOR TO THE OHIO BRASS COMPANY, OF MANSFIELD, OHIO, A CORPORATION OF NEW JERSEY.

TROLLEY CATCHER AND RETRIEVER.

1,277,421.

Specification of Letters Patent.

Patented Sept. 3, 1918.

Application filed July 9, 1917. Serial No. 179,831.

To all whom it may concern:

Be it known that I, WALTER W. HUNZICKER, a citizen of the United States, residing at Mansfield, in the county of Rich-
5 land and State of Ohio, have invented cer-
tain new and useful Improvements in Trol-
ley Catchers and Retrievers, of which the
following is a specification.

This invention relates to improvements in
10 trolley catching and retrieving devices, and
consists in the construction and arrangement
of parts hereinafter more fully described
and claimed.

The object of my invention is to provide
15 a means for engaging the reel to prevent the
winding up of the rope.

Another object of my invention is to pro-
vide a means for retaining the spring in
wound up relation with respect to the reel.

20 Another object of the invention is to pro-
vide a latch which is adapted to engage a
slot in the reel, to be retained in engagement
therewith by the action of the spring on the
reel and to disengage the slot by gravity
25 when the reel is moved so as to counteract
the action of the spring.

A further object of the invention is to
provide a means whereby the operative parts
of the device will be held in a predetermined
30 relation for the purpose of removing or re-
placing the rope, the means engaging the reel
by hand manipulation and disengaging the
reel by gravity.

Other and further objects will appear in
35 the specification, reference being had to ac-
companying drawings, in which—

Figure 1 is a front elevation of a catcher
embodying my invention. Fig. 2 is a side
view of the device. Fig. 3 is a perspective
40 view of a latch.

The same reference characters indicate
the same parts in all of the views. Refer-
ence numeral 1 indicates a case, provided
45 ably secured thereto by any well known
means.

A spool 5, having flanges 6 and 6', a
groove 7, on which the trolley rope 8 is
wound, is rotatably mounted on the stud 3.
50 The trolley rope 8 is detachably attached
to the spool 5 by means of the slot 9 or any
other well known means.

A rope tensioning spring 10 is arranged
within the case 1 and connected with the
55 spool 5, in a manner, as to resist the un-

winding of the rope 8 for the purpose of
keeping the slack out of the rope at all
times.

The above combination and the arrange-
ment of the parts, briefly outlined, will be 60
readily understood by those familiar with
devices of this character and has been se-
lected by me for the purpose of illustrating
my invention, which consists of the follow-
ing:

65 On the case 1, lugs 11 are provided for
the purpose of pivotally mounting a latch
12, which has a slot 13 formed in one end
thereof and provided with stop lugs 14,
preferably made integral therewith, adapt- 70
ed to contact with the lugs 11 whereby fur-
ther movement of the latch 12 will be re-
stricted.

The flange 6' of the spool 5 has an open-
ing 15 formed therein which communicates 75
with the recess 16 whereby the nose 17 is
formed.

The opening 15 is adapted to receive the
slotted end of the latch 12, which when in-
serted therein, and by means of the nose 17 80
entering into and engaging the slot 13 the
parts will be interlocked, and further move-
ment of the spool in a predetermined direc-
tion will be prevented. When it is desired to
release the parts, the spool 5 is turned in 85
the direction as to remove the nose 17 from
the slot 13 which when disengaged will per-
mit the latch 12 to swing out of the open-
ing 15.

90 From the foregoing description the use
and operation of my invention will be
readily understood. When it is desired to
remove or replace the rope, or to prevent
further winding up of same, movement of
the spool 5 is arrested by means of the latch 95
12 which engages therewith by hand ma-
nipulation. In order to restore the device
to its normal operative position the latch
12 is disengaged, by gravity, from the spool
5 as hereinbefore described.

100 It is evident that various changes may be
made in the construction, combination and
arrangement of the parts without departing
from the spirit and scope of my invention.

105 What I claim is:

1. In a trolley tender, the combination of
a case, a spool provided with flanges rota-
bly mounted therein, a recess in the spool
into which a nose projects, a latch pivoted
to move in angular relation to the plane of 110

the spool flanges and movable into said recess to prevent rotation of the spool, said latch being provided with an opening to receive the nose when the latch is in engagement with the spool for the purpose of interlocking the parts.

2. In a trolley tender, the combination of a case, ears on the case, an axle in the case, a latch provided with an opening pivotally mounted between the ears to move in a plane coinciding with the axis of the axle, stop lugs on the latch to limit the movement of the latch in one direction by engagement with the ears, a spool provided with flanges rotatably mounted on the axle, one of the flanges having a recess for the reception of the latch to hold the spool against rotation in one direction, and a projection within the

recess to coöperate with said opening in the latch to prevent disengagement of the latch 20 from the spool when in engaged relation.

3. In a trolley catcher, the combination of a case, a spool provided with a flange rotatably mounted therein, a spring for rotating the spool, and means for locking the spool 25 against rotation by said spring comprising a recess in the spool, a latch provided with an opening mounted to move in a plane in angular relation to the spool flange and movable into said recess, and a projection within 30 said recess receivable within the opening in the latch to interlock the parts against accidental disengagement.

In testimony whereof I affix my signature.

WALTER W. HUNZICKER.
